ELEVATOR LINK RETAINER

Harry V. De Coursey, Houma, La., assignor to
 Byron Jackson Co., Huntington Park, Calif., a
 corporation of Delaware

Application August 10, 1936, Serial No. 95,186

6 Claims. (Cl. 294—90)

This invention relates to well casing elevators such as are used for raising and lowering well casing, drill pipe or tubing in a deep well such as an oil well. More particularly the invention relates to improved latching means for releasably retaining the elevator links in the elevator ears.

Well casing elevators usually comprise a pair of substantially semi-circular members hingedly connected together at one end and provided with a spring latch to releasably connect the free ends of the members whereby the elevator can be applied to and removed from the pipe. Well casing elevators are supported from a hook and traveling block by means of a pair of elevator links one end of which engages ears formed on the elevator and the other ends engage the hoisting hook. The elevator ears extend laterally of the elevator and are oppositely disposed. If the elevator is of the so-called "center latch" type the ears are disposed one on each door. If the elevator is of the so-called "side door" (body and door) type the ears are both on the body member. Elevator ears are usually bifurcated substantially horizontally forming upper and lower forks, that is, they are formed with a substantially horizontal slot extending inwardly and somewhat upwardly from the outer end of the ear and adapted to receive the lower end or eye of an elevator supporting link. Thus the elevator link pulls upwardly on the upper fork of the ear, and the lower fork serves as a bumper for the lower end of the elevator link in case the pipe or elevator should "hang up" while running in the well. In order to prevent the elevator links from getting out of the slot between the forks it is customary to block the opening with some sort of bolt or latch.

It is an object of the present invention to provide improved elevator link retaining means which will become latched automatically when the elevator links lift on the elevator ears.

Another object is to provide an improved elevator link retaining means and latch whereby the latch will automatically engage the free end of the link retainer when the elevator is raised by means of the elevator links.

The preferred form of my invention is illustrated in the accompanying drawings wherein:

Figure 1 is a front elevation, partly in cross section of an elevator equipped with my improved link retaining means.

Figure 2 is a side elevation of the elevator shown in Fig. 1.

Figure 3 is a fragmentary section taken through a modified form of link retainer arm and latch.

Figure 4 is a fragmentary end elevation of the link retainer shown in Fig. 3.

Figure 5 is a perspective view of the latch shown in Figs. 1 and 2.

Figures 1 and 2 illustrate a typical "center latch" type of elevator equipped with my improved

elevator link retainer. The elevator comprises a pair of body members 1 and 2 hingedly connected together at one end as indicated at 3 and provided with a spring pressed latch 5 adapted to releasably connect their free ends. The body members 1 and 2 are provided with a pair of oppositely disposed laterally extending ears 7 and 8. The ears 7 and 8 are bifurcated substantially horizontally to form an upper fork 10 and a lower fork 11. Elevator links are indicated at 13 being shown in the hoisting position.

The upper forks 10 are each provided with a recess 12 adapted to receive an elevator link retaining arm 14. Each of the arms 14 is pivotally secured to one of the upper forks 10 by a pivot pin 16. The pivoted end of each arm 14 is provided with an integral, inwardly extending finger 18 which lies in the recess 12 when the arm 14 is in the closed position (as shown in the drawings) so that its under edge is substantially flush with the link engaging portion of the upper fork. Thus when the elevator is raised by means of the links 13 the links will bear against the fingers 18 and force the arms 14 to the fully closed position.

The lower ends of the arms 14 extend thru slots 20 in the lower forks 11. Each of the arms 14 is provided at its free end with a pair of laterally extending lugs 22 forming a T-shaped head on the end of the arm 14.

A latch member 24 (Fig. 5) is provided for securing the arm 14 in the closed position. The latch preferably consists of a hub 25 having a pair of spaced arms 26 which, with the hub, form a U-shaped latch member. The ends of the arms 26 are provided with downwardly projecting hook-shaped lugs 27 adapted to engage the lugs 22 on the T-shaped head of the retaining arm 14. The latch 24 is pivotally mounted in a recess 29 formed in the lower side of the lower fork 11, a pivot pin 30 extending through the hub 25. The latch 24 is yieldably held in the latch engaging position by means of a suitable spring, such as the torsion spring shown at 32.

With the latch arrangement described above, movement of the link retaining arm 14 to the closed position when actuated by the links 13 bearing against the fingers 18 will cause the T-head on the retaining arm to engage the hook-shaped lugs 27 on the spring-pressed latch 24. Thus the elevator can not pick up the pipe without the link retainer arms 14 being in the closed and latched position.

To remove the elevator links 13 from the elevator it is only necessary to raise the latches 14 and lower the links 13, whereupon the links will push the link retaining arms outwardly and allow the links 13 to be disengaged from the ears 7 and 8.

In Figs. 3 and 4 I have shown a modified form of latch and link retainer arm. Instead of providing the link retainer arm with a T-shaped

head I provide the arm 14a with an opening 36 through which the latch 24a is adapted to extend. The latch 24a is provided with a shank having a downwardly extending hook-shaped lug 27a at one end adapted to engage the end of the arm 14a, and at its other end is pivotally connected to the lower fork 11a of the ear. The latch 24a is yieldably urged toward the arm engaging position by a torsion spring 32a.

19 The upper end of the link retaining arm 14a is similar to that shown in Figs. 1 and 2.

If it is desired that the link retaining arm 14a shall engage the lower fork 11a to take up a part of the stress when the elevator is under heavy load I provide the arm 14a with a recess 38 adapted to extend around the end of the lower fork 11a. The lower wall of the recess 38 and the under face of the fork 11 are struck substantially on a radius from the center of the pivot pin 16a as indicated at 40. Thus when the elevator is under heavy load the faces of the recess 38 and the fork 11a will engage at 40 and relieve the stress on the upper fork 10a.

I claim:

25 1. A well casing elevator with a pair of oppositely disposed, laterally extending, bifurcated supporting ears each comprising an upper fork and a lower fork, a recess in the under side of said upper fork, a link retaining arm pivotally attached at its upper end to said upper fork adjacent the outer end thereof and adapted to extend across the opening between said forks, a finger integral with said retaining arm at the pivoted end thereof projecting inwardly toward the vertical axis of the elevator and adapted to lie in said recess when said arm is in the closed position so that its under edge is substantially flush with the link-engaging portion of said upper fork, and spring-pressed latch means for automatically securing the free end of said arm to the lower fork when the arm is closed, said latch means being accessible from the outer side of said arm when the latter is in closed position.

2. A well casing elevator with a pair of oppositely disposed, laterally extending, bifurcated supporting ears each comprising an upper fork and a lower fork, a recess in the under side of said upper fork, a link retaining arm pivotally attached at its upper end to said upper fork adjacent the outer end thereof and adapted to extend across the opening between said forks, a finger integral with said retaining arm at the pivoted end thereof projecting inwardly toward the vertical axis of the elevator and adapted to lie in said recess when said arm is in the closed position so that its under edge is substantially flush with the link-engaging portion of said upper fork, and spring-pressed latch means on said lower fork adapted to automatically engage the free end of said arm when said arm is moved to the closed position, said latch means being accessible from the outer side of said arm when the latter is in closed position.

3. A well casing elevator with a pair of oppositely disposed, laterally extending, bifurcated supporting ears each comprising an upper fork and a lower fork, a recess in the under side of said upper fork, a link retaining arm pivotally attached at its upper end to said upper fork adjacent the outer end thereof and adapted to extend across the opening between said forks, a finger integral with said retaining arm at the pivoted

oted end thereof projecting inwardly toward the vertical axis of the elevator and adapted to lie in said recess when said arm is in the closed position so that its under edge is substantially flush with the link-engaging portion of said upper fork, said link retaining arm comprising a shank portion with laterally extending lugs on the free end thereof forming a T-shaped head, a slot in said lower fork adapted to receive the shank of said arm, and a spring-pressed latch member mounted on said lower fork and adapted to automatically engage said T-shaped head when said arm is moved to the closed position, said latch means being accessible from the outer side of said arm when the latter is in closed position.

4. A well casing elevator as defined in claim 3 in which the spring-pressed latch member comprises a U-shaped member mounted on a horizontal pivot on said lower fork and provided with downwardly projecting hook-shaped lugs on the ends of the arms of said U-shaped member, said last-named lugs being engageable respectively with the lugs on said retaining arm.

5. In a well casing elevator, a body having a pair of oppositely disposed, laterally extending, bifurcated supporting ears, each comprising an upper fork and a lower fork, a link retaining arm pivotally attached at its upper end adjacent the outer end of each upper fork and adapted to extend across the opening between said upper and lower forks, a finger integral with said retaining arm at the pivoted end thereof and projecting inwardly toward the vertical axis of the elevator, an inwardly extending recess in the outer end of each lower fork, spring-pressed latch means pivotally mounted wholly within said recesses and adapted to releasably engage the free end of said retaining arms, said latch means being accessible for manual release from the outer sides of said arms when the latter are in closed position, and an inwardly extending slot in the outer end of each lower fork adapted to receive the free end of said retaining arm.

6. A well casing elevator with a pair of oppositely disposed, laterally extending, bifurcated supporting ears each comprising an upper fork and a lower fork adapted to receive an elevator link therebetween, a recess in the under side of said upper fork, a link retaining arm pivotally attached at its upper end to each of said upper forks adjacent the outer end thereof and adapted to extend across the opening between said forks, a finger integral with said retaining arm at the pivoted end thereof projecting inwardly toward the vertical axis of the elevator and adapted to lie in said recess when said arm is in the closed position so that its under edge is substantially flush with the link-engaging portion of said upper fork, an inwardly extending recess in the outer end of each lower fork, latch means mounted wholly within said last named recesses and accessible from the outer side of said arm when the latter is in closed position, said latch means comprising an arm having a hook shaped head adapted to engage the free end of said retainer arm, said latch arm being mounted on a horizontally disposed pivot pin, spring means normally urging said latch toward the locked position, and a vertical slot in the outer end of each of said lower forks adapted to receive the free end of said retainer arm.

HARRY V. DE COURSEY.
